SASH GUIDE AND SEAL

Bernard A. Chaplow, Detroit, Mich., assignor to
 Wholesale Lumber & Millwork, Inc., Detroit,
 Mich., a corporation of Michigan

Application April 24, 1936, Serial No. 76,145

5 Claims. (Cl. 20—69)

This invention relates to a sash guide, and particularly to a sash guide and seal for a pair of relatively slideable window sash.

An object of the invention is to provide an improved sash guide formed of sheet metal which is adapted to be secured to a window frame to provide guideways or grooves in which the sash may slide without binding.

Another object of the invention is to provide a sash guide of the foregoing character having, in addition to the grooves for permitting the free sliding movement of the sash, means for sealing the sash and window frame to prevent the passage of air or moisture.

15 A further object of the invention is to provide a two-part metal sash guide provided with a parting stop located between the sash grooves.

Another object of the invention is to provide a two-part metal sash guide provided with a composite wood and metal parting stop.

20 A further object of the invention is to provide a metal sash guide formed of two parts adapted to be assembled together in edgewise relation to provide a substantially centrally located parting stop in which each of the sections is provided with a sash groove having a weather strip located therein.

A further object of the invention is to provide 30 a sash guide or a combined sash guide and weather seal composed of two separate and independent parts capable of being produced in a single rolling machine or by a stamping process; and one which is of relatively simple construction, inexpensive to manufacture and capable of quick 35 assembly and installation.

The above and other objects of the invention will appear from the following description and appended claims when considered in connection with the accompanying drawing forming a part 40 of this specification.

In said drawing:

Fig. 1 is an inside elevation of a window and frame showing in broken lines, one form of sash guides embodying the present invention.

45 Fig. 2 is a fragmentary horizontal section, on an enlarged scale, taken substantially along the line 2—2 of Fig. 1.

Fig. 3 is a fragmentary perspective view of the sash guide of Fig. 2.

50 Fig. 4 is a fragmentary horizontal section, on an enlarged scale, showing a combined two-part sash guide and seal and associated parts embodying the invention; and

55 Fig. 5 is a view similar to Figs. 2 and 4 showing

a modified form of sash guide and parting stop, embodying the invention.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring particularly to Figs. 1 to 3 inclusive, there is shown one form of sash guide embodying the present invention. As shown, the sash guide

is formed in two parts or sections A and B, the section or strip A having a depressed portion or sash groove 10 and the section or portion B having a sash groove 11. The section A is provided

with a weather strip member or rib 12 and is flanged at its inner longitudinal edge to provide one portion 13 of a parting stop or spacer member C. The outer edge of the strip 10 is inwardly flanged at 14 for a purpose to be hereinafter described.

The section or portion B of the guide has a weather strip or rib 15 similar to the rib 12, and the inner free edge of said section is flanged at 16 to provide the second half or portion of the centrally disposed parting stop C. The outer edge of the section B is inwardly flanged at 17 similarly to the flanged edge 14 of section A.

It will be noted that the parting stop portions or halves 13 and 16 are provided, respectively, with 25 interfitting or nested portions or members which

serve to lock the parts together when the two sections are assembled in edgewise relation. The parting stop portion 13 is formed with a longitudinally extending channel or groove 18 adapted

30 to receive a longitudinal rib or projection 19 formed in the stop portion 16. The upper sash

20 is provided with a saw cut or kerf to receive the weather strip rib 12 and the lower sash 21 is provided with a similar saw cut or kerf to receive the weather strip or rib 15, the saw cuts

35 being preferably slightly larger than the weather strips so as to insure the freedom of relative movement of the sash and strips.

The sections A and B of the sash guide are 40 assembled with their respective sash and the inner faces or walls of the parting stop portions or members 13 and 16 are brought into edgewise

45 abutting relation, whereupon the whole assembly is slipped into the trackway or recess formed in

50 55

the window frame. When assembled the base of the sash guide sections lies flat against the window frame member 22 with the flange 14 engaging the blind stop 23. The inner window stop 24 is secured in place with relation to the window frame member 22 and when in place, the inner edge of the stop 24 engages the outer face of the flange 17. The metal guide sections A and B are preferably secured in place upon the window frame member 22 by means of nails or screws (not shown) which may be passed through pre-formed holes in the base portions 10 and 11 of the guide. When the parts are assembled as above described, it will be seen that each sash is located in and engages the sash groove formed in its respective guide member, the inner edge of each sash abutting the adjacent flange of the parting stop section or portion. The outer edge of each sash is in contact with the metal edge flanges 14 or 17 of the sections A and B, respectively.

By virtue of the above described construction it is possible to first assemble the section A of the guide with its sash 20 and insert the assembly in the window frame, and thereafter assemble the guide portion B with the lower sash 21 and then insert these assembled parts in the window frame. The present construction permits of the above method of assembly and materially reduces the time factor in assembling the window sash with the window frame. With previous forms of sash guide structures it has been necessary to assemble the sash guide with both sash and to then insert the entire assembly into the window frame.

Referring particularly to Fig. 4 there is shown another embodiment of the present invention in which the sash guide of the preceding figures is modified to include sealing means for the window and frame. In this form of the invention the base portions 10 and 11 of the guide sections or strips A and B, respectively, the weather strip ribs 12 and 15 and the separable parting stop members or portions 13 and 16 are identical with these parts shown in the preceding views. The outer edge flange 14 of section A, however, is different, as is the edge flange 17 of section B. In lieu of the single flanges 14 and 17 of the preceding form, the metal at the outer longitudinal edge of guide section A is reversely or return bent at substantially a right angle to the base 10 to provide a substantially U-shaped or double flange, while the metal at the outer edge of section B is similarly reversely bent to provide a double or U-shaped flange 26. The outer leg of flange 25 is bent outwardly at right angles to provide a longitudinally extending sealing strip or member 27 and the outer leg of the flange 26 is similarly bent outwardly at right angles to provide an extension or longitudinally extending sealing member or portion 28. It will be seen that the sealing strips or portions 27 and 28 extend outwardly in substantially the plane of the base portions 10 and 11.

When the sections A and B are assembled together and with the upper and lower sash 20 and 21, these assembled parts are inserted in position against the window frame member 22, the guide sections A and B being secured in place in any suitable manner, as by means of nails or screws passing through the metal of the guide sections. The blind stop 23 has a saw cut or kerf formed therein to receive the sealing flange 27 and the inner window stop 24 has a cut-away portion to receive the sealing flange 28 so that when the member 24 is attached to the frame member

22, the flange 28 is clamped between these two members. It is to be noted that the U-shaped flanges 25 and 26 are located, respectively, between the blind stop 23 and the back or outer face of the sash 20 and the inner window stop 24 and the front or inner face of the sash 21. Thus the sections or halves 13 and 16 of the parting stop provide guides for the adjacent inner faces of the upper and lower sash 20 and 21 and the inner legs of the U-shaped flanges 25 and 26 provide guides for the outer faces of the sash 20 and 21, respectively. Thus the sash slide in pre-formed metal grooves and have a wood to metal contact to prevent sticking due to warping, expansion or contraction of the window frame members. The flanges 27 and 28 provide sealing members to prevent the ingress of air or moisture between the sash and sash frame from the exterior to the interior of the building.

Referring particularly to Fig. 5, a further embodiment of the present invention is shown. In this form, the frame member 22 has applied to its inner face a centrally disposed wood block or parting stop 29 having in its outer face a substantially centrally disposed longitudinal saw cut or groove to receive the parallel inner flanges 13a and 16a of the metal parting stop members or portions 13 and 16, respectively. In all other respects the sash guide of Fig. 5 corresponds to the form shown in Figs. 1 to 3 inclusive. The method of assembly of this form may be substantially as follows: The section A of the sash guide is first applied to the face of the frame member 22 with its outer longitudinal flange 14 engaging the inner face of the blind stop 23, it being understood that the section A is first applied to the upright edge or face of the upper sash 20. When the assembled sash guide A and sash 20 are applied to the window frame, the parting stop section 13 engages the wood parting stop 29 with the flange 13a thereof resting within the saw cut formed therein. The section B of the guide is now applied to the lower sash 21 and the assembled parts slipped into position against the inner face of the window frame member 22, the half or section 16 of the metal parting stop engaging the wood stop 29 and the flange 16a of said metal stop portion fitting within the groove or saw cut formed in the wood stop member. After the upper and lower sash and sash guide sections have been installed as described the inner window stop 24 is then secured to the face of the frame member 22 in which position the flange 17 contacts the inner edge or face of the member 24. It will be noted that as in the case of the form of Figs. 1 to 3, the longitudinal outer edge flanges 14 and 17 extend inwardly from the base portions of the guide at an angle slightly less than a right angle. Thus, when the guide parts A and B are installed in the window frame they are held under compression due to the flexibility of these flanges. By virtue of the present form of the invention the sash 20 and 21 also have free sliding movement with a wood to metal contact.

As shown, the embodiment of the invention illustrated in Fig. 5 includes a composite three-part parting stop or separator for the sash. The metal of the flanges forming the sectional parting stop is of sufficient flexibility to cause the flanges to interfit with the wood stop member 29 without the necessity of any auxiliary securing means. It is to be understood that, if desired, the flanges 14 and 17 of the form of the invention shown in Fig. 5 may be modified in

accordance with the structure shown in Fig. 4 without departing from the spirit of the present invention, so that the guide of Fig. 5 will include a weather seal or seals.

5. I claim:

1. A sash guide formed of sheet metal and comprising two separate members formed to provide a parting stop extending substantially centrally thereof when the members are assembled together in edgewise abutting relation, each of said members being formed to provide a sash groove, and a weather strip integral with each of said members and extending into each of said sash grooves, said parting stop having inter-

15 fitting portions.

2. A sash guide formed of sheet metal and comprising two separate members formed to provide a parting stop extending centrally thereof when the members are assembled in edgewise abutting relation, each of said members being formed to provide a sash groove, said parting stop having longitudinally extending interlocking portions, and a weather strip integral with each of said members and extending into each of said sash grooves, the free edge of each member being provided with a flange defining the outer edge of each of said sash grooves.

3. A sash guide and seal comprising sheet or strip metal formed to provide a parting stop extending centrally of the guide, sash grooves located on opposite sides of said parting stop, weather strip ribs formed from said metal and extending into the sash grooves at points spaced

from said parting stop, the outer edges of the metal having return bent flanges defining the outer edges of said sash grooves, and a weather seal formed integral with and extending beyond the edge of each of said flanges in substantially 5 the plane of the base of the guide.

4. A sash guide formed of sheet metal and comprising two separate metal members of substantially identical form, each of said members having a sash groove formed therein, the inner 10 edges of said members having cooperable engaging and separable portions providing a parting stop extending substantially centrally of the sash guide when the members are assembled together in edgewise abutting relation, the outer 15 edges of said members having flanges defining the outer edges of the sash grooves formed in said members, and a weather strip integral with each member and extending into the sash groove.

5. A sash guide and seal comprising sheet or 20 strip metal formed to provide a parting stop extending centrally of the guide, sash grooves located on opposite sides of said parting stop, weather strip ribs formed from said metal and extending into the sash grooves at points spaced 25 from said parting stop, an edge of the metal having an inwardly directed return bent flange defining the outer edge of a sash groove, and a weather seal formed integral with and extending beyond the edge of said return bent flange in 30 the direction of the plane of the base of the guide.

BERNARD A. CHAPLOW.
